UNITED STATES PATENT OFFICE.

EDNA BAIRD AND CANNIE MAY ALIG, OF DES MOINES, IOWA.

DESIGN FOR A DOLL.

59,533.

Specification for Design.

Patented Nov. 1, 1921.

Application filed October 28, 1919. Serial No. 334,083. Term of patent 3½ years.

To all whom it may concern:

Be it known that we, EDNA BAIRD and CANNIE MAY ALIG, citizens of the United States, and residents of Des Moines, in the county of Polk and State of Iowa, have invented a certain new, original, and ornamental Design for a Doll, of which the following is a specification, reference being had to the accompanying drawing, forming part thereof.

Fig. 1 shows a side elevation of the doll.
Fig. 2 shows a back view of the doll shown in Fig. 1 of the drawings.

We claim.

The ornamental design for a doll, as shown.

EDNA BAIRD.
CANNIE MAY ALIG.
